(57) **CLAIM**

The ornamental design for an electric connector, as shown and described.

DESCRIPTION

FIG. 1 is a front elevational view of an electric connector showing my new design;
FIG. 2 is a top plan view thereof;
FIG. 3 is a rear elevational view thereof;
FIG. 4 is a bottom plan view thereof;
FIG. 5 is a right side elevational view thereof;
FIG. 6 is a cross-sectional view thereof, on an enlarged scale, taken along line 6-6 in FIG. 1;
FIG. 7 is a front, top, and left side perspective view thereof;
FIG. 8 is a rear, top, and left side perspective view thereof; and,
FIG. 9 is a front, top, and left side perspective view thereof, in a use condition.
The broken lines in the drawings depict environmental subject matter only and form no part of the claimed design.
